UNITED STATES PATENT OFFICE

WILLIAM A. BICKEL, OF OAK PARK, ILLINOIS, ASSIGNOR OF ONE-THIRD TO HAROLD W. ROBERTS AND TWO-THIRDS TO EARL W. THOMPSON

RACKET STRINGING VISE

Application filed October 14, 1931. Serial No. 568,826.

This invention relates to tennis racket stringing vises and, more especially, such a vise which, with slight changes in size, may be used for stringing other kinds of rackets, 5 such as squash and badminton rackets, and so forth.

A feature of the invention is the combination of the racket head clamp and the handle clamp to provide a simple and effective device of the character indicated; and a further feature resides in the construction of the racket head clamp proper and the handle clamp.

The invention is illustrated in the accompanying drawing, in which—

Figure 1 is a plan view of my improved vise for stringing rackets with a racket frame clamped therein; Fig. 2, a broken plan view with the head clamp shown in the position for 20 stringing the centrally disposed longitudinal strands; Figs. 3, an enlarged broken sectional view of the head clamp taken at the line 3 on Fig. 1; Fig. 4, an enlarged sectional view of the handle clamp, taken at the line 25 4 of Fig. 1; Fig. 5, an enlarged broken sectional view taken at the line 5 on Fig. 2; and Fig. 6, a plan sectional view taken at the line 6 on Fig. 3.

In the drawing, the device is shown as 30 comprising a ribbed bar A; a head-gripping member B mounted on one end of the bar; and a handle-gripping member C mounted on the other end of the bar. D designates a tennis racket having a head 7 and a handle 8.

The member A is preferably a ribbed bar provided with broadened end-portions 9 and 10 adapted to be securely fastened to a work bench or extension plank. The clamping members B and C are mounted on supports 35 11 and 12 sufficiently above the bar A to permit the stringer to work below the racket head without discomfort. Preferably, the bar, the rigid jaws of the gripping members and their supports are cast in one piece.

The handle-gripping member C comprises a base 13 upon which the racket handle rests, a floating jaw 14 and a rigid jaw 15 and an abutment 16. The jaw 15 tapers slightly in 50 the direction of the racket head to conform with the contour of the racket handle at the

point of engagement. The abutment 16 has a threaded bore 17 containing a screw 18 which controls the position of the floating jaw. The floating jaw has a peculiar utility in my device in that it self-centers the racket handle, 55 thereby eliminating any possibility of stringing the racket while the head is in a strained or twisted position causing it to warp.

It is well known that the throat of a tennis racket is one of the weakest spots in its construction. In order to prevent springing or cracking of the throat while the racket is being strung, I have located the handle-gripping member C relatively close to the head of the racket. 65

The head-gripping member B consists of a rigid jaw 19 provided with a set screw 20 and a movable jaw 22 disposed on said set screw and controlled by a knob 21. The rigid jaw 19 has an offset vertical face 23, curved to 70 follow the contour of the inner side of the top of the racket head. The offset face 23 is shallow enough to permit the holes in the racket head to extend above the top face 24 of the jaw when the head of the racket is 75 resting in stringing position.

The jaw 22 has a slightly concave inner surface 26 adapted to engage the top of the racket and an overhanging head 27 to engage the side of the racket as it lies in the 80 vise. The outer surface of the jaw has an upwardly tapering boss 28 adapted to contact with the knob 21 when it is screwed on. The pressure of the knob on the movable jaw forces the lower part of the jaw against the 85 shoulder 25 of the support 11, forming an abutment which tends to move the upper part of the jaw into engagement with the racket head in a diagonal direction.

As shown in Figs. 3 and 6, the shoulder 25 90 is provided with a stud 29 adapted to engage a groove 30 in the movable jaw when the jaw is forced into gripping position, thereby preventing the movable jaw from rotating with the knob and from securing the 95 racket head in a twisted position.

The jaw 22 is provided with a longitudinal slot 31 penetrated by the set screw, permitting the jaw to be rotated thereon when disengaged. To string the centrally disposed 100

longitudinal holes, the jaw is rotated to a horizontal position, as shown in Figs. 2 and 5, and in that position, is brought into engagement with the racket head. As shown in Figs. 3 and 4, a lining preferably of wool felt covers all the faces contacting with the racket.

The foregoing detailed description has been given for clearness of understanding only 10 and no unnecessary limitations should be understood therefrom, but the appended claims should be construed as broadly as permissible, in view of the prior art.

What I regard as new, and desire to secure 15 by Letters Patent, is:

1. A racket stringing vise comprising in combination a handle-gripping member and head-gripping member; said handle-gripping member consisting of a base, a rigid jaw 20 and an abutment extending from said base and a floating jaw controlled by a screw adapted to self-center the racket handle, said head-gripping member consisting of a rigid jaw provided with angularly related faces 25 adapted to support the racket head on its lower side and engage it on its inner side, and a movable jaw disposed on a set screw and having surfaces adapted to engage the sides of the racket head opposite to those engaged 30 by said rigid jaw; and means to keep the movable jaw in alignment with said rigid jaw.

2. An integral racket stringing clamp comprising: a racket handle-gripping member and a racket head-gripping member mounted on a bar, said handle-gripping member having a channel in a plane longitudinal to the bar and said head-gripping member having a channel in a plane trans- 40 verse to the bar.

3. An integral racket stringing clamp comprising: a racket handle gripping member and a racket head-gripping member mounted on a bar; said handle-gripping member comprising a shank having abutments at opposite ends, one of said abutments serving as a fixed jaw, an operating screw mounted on the other abutment and a movable jaw mounted on said shank, said head-gripping member 45 comprising a rigid jaw having angularly related faces and a movable jaw having faces adapted to engage the sides of the racket head; and means of adjusting the movable jaw.

4. An integral racket stringing clamp comprising: a racket handle-gripping member and a racket head-gripping member mounted on a bar, said handle-gripping member comprising a shank having a surface to support said handle, abutments at opposite ends of said shank, one of said abutments serving as a fixed jaw, said fixed jaw tapering in the direction of the head-gripping member, an operating screw mounted on the other abutment, and a movable jaw mounted on said

shank adapted to self-center the racket handle; said head-gripping member comprising a rigid jaw having angularly related faces adapted to support the racket head on its lower side and to engage it on its inner side; 70 and a movable jaw having faces adapted to engage the sides of the racket head opposite to those in engagement with said rigid jaw faces; means of adjusting the movable jaw; and means of preventing distortion of the 75 racket head while it is engaged by the clamp.
